Attorney

UNITED STATES PATENT OFFICE.

CLARENCE H. HAPGOOD, OF TOLEDO, OHIO, ASSIGNOR TO TOLEDO SCALE COMPANY, OF TOLEDO, OHIO, A CORPORATION OF NEW JERSEY.

WEIGHING SCALE.

Original application filed July 25, 1914, Serial No. 853,061. Divided and this application filed April 26, 1920. Serial No. 376,724.

To all whom it may concern:

Be it known that I, CLARENCE H. HAPGOOD, a citizen of the United States, residing at Toledo, in the county of Lucas and State 5 of Ohio, have invented certain new and useful Improvements in Weighing Scales, of which the following is a specification.

This application is a division of my co-pending application Ser. No. 853,061, filed 10 July 25, 1914.

My invention is designed more particularly with reference to platform scales and is shown in the drawings accompanying this specification as embodied in a device of 15 this character, but in certain of its features it is applicable to other forms of scale, and it is to be understood that the specific disclosure is for the purpose of exemplification only. The scope of the invention is defined 20 in the following claims, in which I have endeavored to distinguish it from the prior art so far as known to me without, however, relinquishing or abandoning any portion or feature thereof.

25 Referring now to the accompanying drawings:-

Figure 1 is a side elevation, partly in section, of the preferred form of my scale;

Figure 2 is a plan view partly in section 30 and with parts removed, as will hereafter appear, to more fully disclose certain other parts; and

Figure 3 is an elevation on an enlarged scale but partly broken away and in section 35 showing the counterbalancing mechanism, the view being taken from the right of Figure 1.

The same symbol of reference is applied 40 to each of the parts wherever it may occur throughout the several views.

Referring first to Figure 1, the base or leverage casing 7 is preferably formed of cast metal and provided on the interior thereof at 8 and 9 with pairs of knives from

45 which the leverage system is suspended. Said leverage system comprises a long lever 10 which is or may be cast in any form desired, and comprises a longitudinal member 11 (see Figure 2) and a pair of transverse members 12, 13, each of which carries knives 14, 15 at its opposite ends, the lever being suspended by knives 14 and loops or stirrups 16 from the knives 8 heretofore mentioned, upon the base. The particular form

of the loops or stirrups is not essential to 55 the present invention, but I have shown the loops as comprising an inverted U-shaped metal strip 17 looped over the knives 8 and embracing between its side members a block 18 having a seat for the knife 14 of the lever. 60 The knives 15 upon the ends of the transverse member 13 are for the support of the platform, as will presently appear. A second or short lever member comprises a 65 longitudinal member 19 and a pair of transverse members 20, 21, having knives 22, 23 at their respective opposite ends, the knives 22 on transverse member 20 being connected by loops or stirrups like those described above with knives 9 referred to above, upon 70 the interior of the base of the scale, and the knives 23 supporting the forward end of the platform, as will presently appear. The longitudinal member 19 of the secondary 75 lever is arranged to one side of the vertical plane of the corresponding member of the main or long lever and the two levers are connected together at an intermediate point by a stirrup member or loop 24 embracing laterally extending knives 25, 26 upon the 80 main and secondary levers respectively. The platform 27 of the scale is mounted in an opening in the base and provided with legs 28, 29 having suitable bearing blocks 30, 31 in their lower ends, legs 28 resting upon the 85 knives of the transverse members of the main lever and legs 29 similarly resting upon the knives of the transverse member 21 of the secondary lever. It will now be seen that as the forward end of the main lever 90 is supported as usual by the counterbalancing mechanism, the secondary lever is supported therefrom by the loop 24 and exerts an upward pull upon the stationary knives 9. Thus, the weight of this part of the device is distributed between the knives 8 at 95 the forward end of the scale base and the counterbalancing mechanism.

Upon the rear end of the scale base is mounted a column 32 which at its upper end 100 supports a casing 33 for the counterbalancing mechanism. The upper end of the column is somewhat enlarged and carries a main beam 34 which is pivoted at 35 therein, and connected to the leverage system in 105 the base of the scale by the usual link 36. The beam extends through the walls of the column at opposite ends, as at 37, 38, and is

formed at one end with a forwardly extending branched arm 39, to the members of which are attached tare or capacity beams 40, 41. The other ends of said beams are attached to an arm 42 at the other end of the beam. A loading box 54 is attached to one end of the main beam 34. This feature is described in detail and claimed in my original application above referred to.

10 The tare and capacity beams just referred to are not employed in the normal use of the scale but only when it is desired to weigh tare or use the scale beyond the capacity of the automatic counterbalancing mechanism. The latter comprises a pair of pendulums 62, 62, which are suspended from suitable bearings 63, 63 in the casing 33. Preferably these bearings are mounted upon brackets 64 depending from the upper portion 15 of the casing. Each of these pendulums is provided with a segment 65 and the two segments are connected by ribbons 66 with an equalizer member 67. To the latter is pivoted a loop or eye 68 from which connection is made to the beam of the scale by a suitable link 69. As usual in pendulum scales, a load placed on the platform thereof through the intermediate connections which have been described raises the pendulums until the load is counterbalanced. The 20 inward swing of the pendulums is limited by a pair of buffers 70, 70 mounted upon a bracket 71 formed integral with the casing. To each of the pendulums is also rigidly attached a second segment 72 and the two segments are connected by ribbons 73 with an equalizer bar 74 from the center of which a rack bar 75 extends upward and carries a rack 76 which engages a pinion 77 upon the 25 shaft of an indicator hand 78. The hand operates as usual with a circular scale 79. The rack may be maintained in engagement with its pinion by an anti-friction roller 80 and a weight 81 mounted eccentrically there- 30 of on the side towards the pinion. From the center of the equalizer bar 74 is suspended a poise plate or support 82 upon which may be placed poises 83 of a weight sufficient to counterbalance the other parts 35 of the scale.

Obviously, when a load is placed upon the scale platform of the automatic counterbalancing mechanism the pull of the load is transmitted through the link 36 to the beam 34 of the scale and thence through link 69, loop 68, equalizer 67 and ribbons 66 to the pendulums, which are thereupon swung outward until they counterbalance the load of the scale. The movement of the pendulums 40 is, of course, accompanied by a raising of the equalizer bar 74 through segments 72 and ribbons 73, whereby the rack 76 rotates the indicator hand proportionately to the amount of load upon the scale.

65 The distribution of weight in the weight

box 54 and weights 83 is such as to properly counterbalance the other parts of the scale.

While it will be apparent that the illustrated embodiment of my invention herein disclosed is well calculated to adequately 70 fulfill the objects primarily stated, it is to be understood that the invention is susceptible to variation, modification and change within the spirit and scope of the subjoined claims.

Having described my invention, I claim:

1. In a weighing scale, in combination, a pair of platform levers each comprising a longitudinally-extending member, a transverse member at one end of the longitudinally-extending member, fulcrum pivots on said transverse member, arms extending laterally from said longitudinally-extending member, load pivots on said arms, and means connecting said levers between said transverse members and said arms.

2. In a weighing scale, in combination, a pair of platform levers each having a longitudinally-extending member, a transversely-extending member and a pair of laterally-extending arms, said transverse members and laterally-extending arms carrying load and fulcrum pivots respectively, and connecting means pivoted to said levers between said transverse members and laterally-extending arms.

3. In a weighing scale, in combination, a pair of platform levers each having a longitudinally-extending member, a transversely-extending member and a pair of laterally-extending arms, said transverse members and laterally-extending arms carrying load and fulcrum pivots respectively, and connecting means pivoted to said levers between said transverse members and laterally-extending arms, the transverse members of one of said levers lying adjacent the laterally-extending arms of the other.

4. In a weighing scale, in combination, a base, a long platform lever of the second order fulcrumed thereto, a short platform lever of the third order fulcrumed to said base, load pivots on said levers lying between said fulcrums, and means for connecting said levers, said connecting means lying between said load pivots.

5. In a weighing scale, in combination, a pendulum, an indicator, a pair of sectors connected to said pendulum, a power member means connecting said power member to one of said sectors, and a ribbon connecting the other of said sectors to said indicator.

6. In a weighing scale, in combination, a pendulum, a power sector connected to said pendulum, a second sector of greater radius 125 connected to said pendulum, an indicator and means connecting said indicator to said second sector.

7. In a weighing scale, in combination, a pair of oppositely-swinging pendulums,

- power sectors on said pendulums, other sectors on said pendulums, an indicator and means connecting said indicator to the said second sectors.
- 5 8. In a weighing scale, in combination, a pair of oppositely-swinging pendulums, power sectors on said pendulums, other sectors on said pendulums, a pair of ribbons connected to the second said sectors, a member connected to said ribbons, and indicating mechanism connected to said member.
- 10 9. In a weighing scale, in combination, a pair of oppositely-swinging pendulums, power sectors on said pendulums, other sectors of greater radius on said pendulums, a pair of ribbons connected to the said sectors of greater radius, a compensating member connected to said ribbons, and indicating mechanism connected to said compensating member.
- 15 10. In a weighing scale, in combination, load-offsetting means comprising a pair of pendulums, bearings from which said pendulums are suspended, sectors fixed to said pendulums, ribbons connected to said sectors and depending therefrom, means for connecting said ribbons at their lower ends, connections from said means to the load-offsetting means, other sectors mounted upon said pendulum members, ribbons depending from the second said sectors, a cross member connecting said ribbons, rotary indicating means, and connections from said cross member to said indicating means.
- 20 11. In a weighing scale and in combination with the main beam thereof, a casing, load-offsetting means comprising a pair of pendulums mounted in said casing, indicating means, a sector mounted on each pendulum, a ribbon depending from each sector, an equalizer member connecting the lower ends of said ribbons, connections from said equalizer member to the beam, a second sector connected to each of said pendulums, ribbons depending from said second sectors, a compensating bar connecting the last-mentioned ribbons, and connections from an intermediate point of said compensating bar for operating said indicating means.
- 25 12. In a weighing scale and in combination with the main beam thereof, load-offsetting means comprising a pair of pendulums, indicating mechanism, a sector on each pendulum, a ribbon depending from each of said sectors, an equalizer member connecting the lower ends of said ribbons, connections from said equalizer member to said beam, a second sector connected to each of said pendulums, ribbons depending from said second sectors, connections from an intermediate point of said compensating bar for operating said indicating means, and a poise receiver connected to said compensating bar.

CLARENCE H. HAPGOOD.
